UNITED STATES PATENT OFFICE.

GABRIEL LANGÉ, OF PARIS, FRANCE.

MACHINE FOR PRODUCING PRINTED RAILWAY-TICKETS.

No. 810,158.

Specification of Letters Patent.

Patented Jan. 16, 1906.

Application filed April 12, 1901. Serial No. 55,502.

To all whom it may concern:

Be it known that I, GABRIEL LANGÉ, a citizen of the French Republic, residing at Paris, France, have invented certain new and useful Improvements in Machines for Producing Printed Railway-Tickets, of which the following is a full, clear, and exact description.

The object of this invention is to provide a machine for printing railway-tickets for different classes and destinations as they are required for sale, the number of different destinations being almost unlimited. The machine prints the required text on a strip of card, and the ticket thus formed is cut off from the strip and falls into the hand of the operator, who issues it to the traveler. Each of these tickets thus made instantaneously is simultaneously registered by recording its destination, class, and price on strips of paper, called "registering-strips" or "control-strips," which are conveniently placed in the machine for the purpose.

The principal parts composing the machine are as follows:

First. The fixed blocks or dies, which determine the plane in which the impression takes place and which bear the inscription common to all the tickets, the name of the office circulating the tickets, the date, and the class. These dies form the fixed part of the machine, by the side of which the dies forming the movable part of the machine take their place.

Second. A notched drum over which passes an endless chain of any required number of links, each link of which carries two dies fixed side by side. The drum is turned by means of a hand-wheel, which causes at will any die carried on the links of the chain to appear by the side of the fixed blocks in the printing-plane. These movable blocks bear the text necessary to complete the printing of the tickets.

Third. Two parallel and independent beams each carrying the ticket and control strips and each of which when oscillated by its lever swings and places the strips in contact with the blocks, (fixed and movable,) which in their turn have previously been inked by an ink-roller, thus printing the complete text of one ticket and a record thereof upon the said control-strip. Each beam is provided with the necessary apparatus for advancing the ticket or control strips gradually, and,

further, the ticket-beam has a knife for cutting off the tickets to a suitable size.

Fourth. Two operating-levers, combined with other mechanism and connected to the two beams, to render all irregularities of working impossible.

In order to make the construction and working of my machine clear, I have illustrated it by means of the accompanying drawings, in which—

Figure 1 is an end view with the outside casing removed and the main lever shown in its middle position. Fig. 2 is a back view of the machine; Fig. 3, a plan of the two print-beams and the mechanism appertaining to the same; Fig. 4, a plan of a ticket; Fig. 5, a plan of a piece of the control-strip. Fig. 6 is a front view of the complete machine. Fig. 7 is a side view of Fig. 6. Figs. 8 and 9 are enlarged detail views of the racks, pawls, and contiguous parts. Figs. 10 and 11 are enlarged detail views of the cutting devices. Fig. 12 is an enlarged side view, parts being broken away, of a portion of the machine.

As shown in Fig. 1, the machine is built up of a framing *a*, carrying the printing-table *b*, on which frame are mounted the dies or blocks *c* and also the various shafts and axles of the mechanism composing the machine and also a horizontal shaft *d*, on which are keyed a hand-wheel *e* and a drum *f*, having notches *g* in its periphery into which the links of the endless chain *h* fit. It is understood that there are two dies *c*; but as they are alike in their nature and mode of operation a description of one will suffice for both. The drum carries the rim *i* at one end provided with ratchet-notches *j*, in which the roller *k* of the lever *l* engages at the time that one pair of the blocks *m*, carried on each of the links of the chain *h*, is exactly in the printing-plane of the dies *c*. The same notches *j* at each end of the drum at the fall of either of the levers *n* engage with a pin *o*, which is secured to one of the levers *n* and which slides in guides *p*, fixed to the frame *a* of the machine. This pin holds the drum *f*, and consequently the endless chain of blocks, perfectly immovable while the ticket is being printed at *c*.

In order to assure correct numbering of the tickets and perfect impressions of the same, an arrangement described hereinafter compels the operator to finish any stroke he has commenced, preventing thus the unlaw-

ful manufacture of tickets. This arrangement consists of two pairs of toothed plates *q* and *r*, with the teeth relatively reversed with respect to one another, which plates are fixed one end to the frame *a*, the other end to the printing-table *b*. These ratchet-plates are fixed one on each side of each main lever *n*, which works in a vertical plane and carries the two pawls *s* and *t*, which pawls engage in the two ratchet-plates in opposite directions and on opposite sides of *n*.

Figs. 8 and 9 show clearly in detail the racks, pawls, and other contiguous parts, and it is here seen that the racks have between them a space sufficient for the manipulation of the lever *n*, and the pawls alternately engage in their respective racks *q* and *r*, and each of these pawls is pushed toward its rack by a spring *a*³, wound round their common axis *b*³, carried by the lever *n*.

The pawls *s* *t* are loosely mounted on the same axis, but held at such an angle by the springs that when one pawl is engaged in its ratchet the other pawl is held out of engagement, the pawls being operated alternately as the lever *n* reaches the end of its stroke by suitably-bent arms *u*, fixed on the ratchet-plates and projecting over the rack-teeth, so as to come against and force one pawl away from its teeth when the lever *n* reaches the end of its stroke in the one direction, at the same time bringing the other pawl into action. The pawls are maintained in either of their extreme positions by spring-catches *x* *y*, which engage with shoulders on their respective pawls only while the pawl is out of action and are alternately acted upon by stops *v* to release the pawls at the end of the stroke of the lever *n*.

A little before the end of the descending course of the lever a fixed stop *u* encounters a shoulder *c*³, formed on the pawl *s*, and compels it to separate from its rack *q*, and this swinging of the pawl *s* enables the catch *x*, acted upon by the spring *d*³, to engage behind a projection *e*³ on said pawl and holds it thus in a position of rest during the rising of the lever. After the disengagement of the pawl *s* and while the lever *n* is completing the remainder of its downward movement the lower stop *v* will encounter catch *y* and release the pawl *t*, which at once engages the teeth of its rack *r* under the action of spring *a*³. What has been accomplished for the pawls against the lower stop *v* will be accomplished at the upper stop in the same manner.

In its upward and downward stroke the oscillating movement of each lever *n* is communicated to a connecting-rod *b*', provided for oscillating one of the printing-beams *d*' about the fulcrum *c*', against which printing-beam the strip *e*', which receives the impression, presses and passes once over the cutting-blade *f*', held in the toothed rack *g*'. This rack is in gear with a toothed quadrant

h', pivotally mounted between the said bars of the frame and provided with a tail-rod *v*.

Figs. 10 and 11 show clearly the cutting devices, and in these figures is shown the printing-beam *d*' at an intermediate position, 70 the rack *g*', the knife-carrier *f*', and the lever *i*', with notched sector *h*', being at their working position, which was given to them when the lever *i*' struck against the cross-bar *l*'. The beam *d*' will oscillate at *c*', and the paste-board *e*' passes between the beams *d*' and the fixed dating-stamp *c*, then between the cutting-blade *f*' and the counter-blade *f*³, carried by the beam *d*'. The blade *f*' being rigidly connected with the rack *g*', when the beam accomplishes its ascent the lever *i*' of the sector *h*' encounters the stop *j*', which makes it oscillate and raises the blade, as in Fig 11. The ticket is then cut and falls onto any suitable plate, table, or receptacle that 85 may be provided for the purpose. In the descent the beam *d*' causes lever *i*' to meet with the fixed cross-piece *l*', forming part of the inking-frame *m*', which brings back the lever *i*' and the blade *f*' to the position shown 90 by Fig 10.

The strips *e*' are of indefinite length; but their width must be adapted to the size of the machine. They are rolled on reels *n*', carried on standards *o*' on the frame *a*. A 95 roller *p*' guides the strips. The paper *e*' passes under the roller *p*' and engages between the roller *q*', having three pins *q*³ and a roller *r*'. In this machine, the length of the ticket being determined by the width of the strips *e*', the breadth of the said ticket is controlled by the amount of advance imparted to the strip by a roller *q*', mounted in each of the printing-beams *d*'. By this arrangement the card is gripped between the roller *q*' 105 and the roller *r*'. At each oscillation from below upward of the beam *d*' one of the pins *q*³ is caught by the catch *s*', which causes the roller *q*' to turn a third of a revolution—an amount corresponding to the width of the 110 ticket. The catch *s*' is joined to the table *b*, and a spring *g*³ presses it against the pins *q*³. The paper also passes under the printing plane *z*', made of rubber or leather, and finally over the cutting-blade *f*', which detaches the 115 ticket printed by the pressure which was given it during the descent of the beam onto the dies *c*, fixed on the table *b*.

The inking of the dies *c* and the corresponding blocks *m* is performed by an inking-roller *t*', held by a spring *u*', mounted on a rocking lever *m*', having its fulcrum on the frame *a*, which lever in its turn is pushed toward the parts to be inked by a spring, but which a roller *v*', carried on the printing-beam *d*', 125 causes to recoil at the right moment by pressing on the edge of the oscillating plate *m*', which in this case acts as a cam.

Quite independent from the above-described motion each printing-beam *d*' carries 130

a control strip or band x' , which is wound on a reel y' , (see Fig. 1,) from whence it passes to a part of the printing-beam d' , covered with an india-rubber pad z' . It then turns 5 upward over the roller a^2 and returns to the reel b^2 , which effects the pulling of the strip.

The pulling of the control-strip is effected by means of a small lever c^2 , carrying at one end a ratchet-pawl d^2 , engaging in a ratchet-wheel e^2 , fixed on the reel b^2 , the tailpiece of which lever comes into contact as the printing-beam rises with an adjustable screw f^2 , provided for that purpose. The lever in its oscillation causes the said ratchet-wheel e^2 to 10 advance a distance of one tooth, and a locking-pawl g^2 , pivoted to the pivot of lever c^2 , locks the said ratchet-wheel and prevents the printed strip from unrolling.

As shown in Fig. 2, each block m is divided 20 into two parts—one for printing the ticket, the other for printing the control-strip.

The series of printing-blocks, constructed 25 suitably for different stations, arranged side by side and in two parallel series and these blocks when placed in the proper position relatively to the fixed dies compose the text of the ticket.

The numbering of the tickets of the same 30 sort is effected by means of a series of five rollers provided with numerals on their periphery, which are actuated and increase the number they represent in combination by means of a ratchet-wheel h^2 , coupled to the unit-roller. This ratchet-wheel is operated 35 in its turn at each downstroke of the printing-beam d' by means of a catch-rod i^2 , conveniently fixed on the under side of each printing-beam.

The front part of the frame of the machine 40 is provided with a window j^2 , through which the operator can clearly see the numbering of the tickets.

For the various sorts of tickets different 45 machines must be provided, which are supplied with different-colored strips. Thus, for example, for "singles" a machine with yellow strips, for "returns" a machine with red strips is provided, and so on, there being as many machines with differently-colored 50 strips required to form a complete installation as there are various sorts of tickets.

Finally, two similar dies k^2 , one of which is seen in Fig. 1 fixed at the top of the frame a , are actuated separately by a lever l^2 , fixed to 55 each printing-beam d' . Each of these counters shows the number of tickets printed and delivered by the printing-beam which moves them. The number recorded by these counters is visible through two windows m^2 , provided for that purpose.

Having now particularly described and ascertained the nature of my said invention and in what manner the same is to be performed, I declare that what I claim is—

65 1. A machine of the character described,

comprising in combination a supporting-frame, a printing-table, two dies fixed parallel to each other on said table, an endless chain carrying a series of printing-blocks suitable for different stations arranged side by side and in two parallel series, which blocks when placed in the proper position relatively to the fixed dies compose the complete text of the ticket, a notched drum over which the said chain passes, means for turning the drum, 70 two operating-levers, two printing-beams, means intermediate the said levers and the beams, whereby the latter may be operated by said levers, mechanism operated by the said beams for advancing strips of card the 75 length of the width of a ticket in order that they may receive the impression from the fixed dies and block temporarily opposite to them, cutting devices and means intermediate said cutting devices and the beams 80 whereby the tickets are cut off in the manner and for the purpose specified.

2. A machine of the character described, comprising in combination a supporting-frame, a printing-table, two dies fixed parallel to each other on said table, an endless chain carrying a series of printing-blocks suitable for different stations, arranged side by side in two parallel series, which blocks when placed in the proper position relatively to the 90 fixed dies compose the complete text of the ticket, a notched drum over which the chain passes, means for turning the drum, two operating-levers, two printing-beams, means intermediate the levers and beams, whereby the latter may be operated by said levers, mechanism operated by said beams for advancing strips of card the 95 length of the width of a ticket, cutting devices, means intermediate said cutting devices and the beams 100 whereby the tickets are cut off, inking devices and means intermediate the beams and said inking devices whereby the latter will ink the blocks and dies after each cutting 105 operation.

3. A machine of the character described, comprising in combination a supporting-frame, a printing-table, two dies fixed parallel to each other on said table, an endless chain carrying a series of printing-blocks suitable for different stations arranged side by side in two parallel series, a notched drum over which the chain passes, means for turning the drum, two operating-levers, two printing-beams, means intermediate the levers 115 and beams, whereby the latter may be operated by the levers, two parallel ratchet-plates having their teeth reversed, said plates being secured to the supporting-frame and printing-table, as described, pawls on the operating-levers adapted to engage with the teeth of the ratchet-plate, as described, and stops arranged at both ends of the ratchet-plates and adapted to operate on the pawls in the 120 manner set forth.

130

4

4. A machine of the character described, comprising in combination a supporting-frame, a printing-table, a die on said table, an endless chain carrying a series of printing-blocks, a notched drum over which the chain passes, means for turning the drum, an operating-lever, a printing-beam, means intermediate the lever and beam whereby the latter may be operated by the lever, mechanism operated by said beam for advancing a strip of card, cutting devices, and means intermediate said cutting devices and the beam whereby the tickets are cut off in the manner specified.

5. The combination of two fixed dies or

blocks, a chain of blocks, means for operating the latter, two printing-beams, operating-levers, mechanism intermediate the latter and the beams, whereby the beams may be operated, and mechanisms operated by the beams to feed and cut a card strip and feed a record-strip in the manner and for the purpose set forth.

In testimony that I claim the foregoing I have hereunto set my hand this 26th day of 25 March, 1901.

GABRIEL LANGÉ.
